UNITED STATES PATENT OFFICE.

PAUL VOLKENBORN, OF COLOGNE-EHRENFELD, GERMANY.

DOUBLE SKIP OR KIBBLE FOR AUTOMATICALLY RECEIVING LOOSE MATERIAL.

1,103,387.

Specification of Letters Patent. Patented July 14, 1914.

Application filed July 24, 1913. Serial No. 780,870.

To all whom it may concern:

Be it known that I, PAUL VOLKENBORN, a subject of the German Emperor, and residing at Cologne-Ehrenfeld, Germany, have 5 invented a new and useful Double Skip or Kibble for Automatically Receiving Loose Material; and I do hereby declare the following to be a full, clear, and exact description of the same.

10 The invention described in U. S. patent application, Serial No. 763194 relates to the movement of the skips by means of oscillating levers which results in a favorable excavating curve and at the same time the 15 path of the pulley block is not increased compared to grabs with closing buckets. The construction described in the above named application has however the disadvantage that the central portion of the material 20 scraped together by the kibbles, is left behind when the grab is lifted, owing to the distance between the cutting edges of the skips.

25 The object of this invention is to take up also this central portion of the material scraped together without departing from the invention described in U. S. patent application Serial No. 763194 which consists in leaving such a distance between the cutting 30 edges of the skips that the material is not crushed. This is effected by giving one bucket an advance relatively to the other in the closing movement, so that in the end position, the cutting edges of the kibbles are 35 not next to each other, as in the above named patent application, but lie under or above each other. It is sufficient that the cutting edges should be approximately vertically above each other. In order, however, to insure 40 a better closing, a kind of overlap can be used, as shown in the annexed drawing. In this arrangement, the leading blade or bucket shovels the material into the one lagging behind, and the whole material scraped 45 together, is taken up, as nothing can fall down between the two skips in the closing position. In spite of that, no jamming or crushing of the particles of the material takes place between the cutting edges of the 50 kibbles.

In the drawings, the figure represents in somewhat diagrammatical form, a double skip or kibble embodying the features of my invention.

55 At the two lower ends of a grab frame 1, are pivoted as at 3, oscillatory supports or

bell crank levers 2. The outer ends of skips 5 and 5' are each rotatably mounted, as at 4, on one arm of the bell cranks 2, while the other arm of each of the bell cranks is pivotally connected as at 6 by a link 7 to a bottom pulley 8 of the hoisting mechanism which is of the ordinary construction and which is vertically movable in the frame 1. Connected also to the lower portions of the 60 bottom pulley 8, are links 9 which are pivotally connected at their other ends to the inner ends of the skips 5 and 5', the general construction thus far described forming no part of the present invention and is 65 specifically disclosed in my application, Serial No. 763,194.

In the application referred to, the links 9 which connect the inner ends of the skips or kibbles 5 to the movable pulley 8 are 70 pivotally connected to the skips 5 at equal distances from their cutting edges, which in the closed position of the skip or kibble are separated from each other and lie in substantially the same horizontal plane.

80 In the present construction, however, each of the links 9 are pivotally mounted at different distances from the cutting edges of the skips and as is shown in the figure, the link 9 which is connected to the skip 5' is 85 pivoted at a greater distance from the cutting edge thereof than is the link which is connected to the skip 5. This will cause the skip 5' to move in advance of the skip 5, when the skips are being closed, and to assume the position shown in full lines in the figure, that is, with the cutting edge of the skip 5' above and out of contact with the skip 5 and preferably overlapping it a slight degree. It is evident that the movement of 90 one skip in advance of the other may also be controlled by changing the pivotal point of the link 7 with the bell crank 2.

95 While I have shown the cutting edges of the skips slightly overlapping each other, yet if they were arranged in the same vertical plane, the loose material contained therein will be prevented from falling out of the grab, and in the claims which are annexed hereto, I deem the term "in substantially a 100 vertical plane" sufficiently broad to cover either of these two constructions.

105 Having now described my invention, what I claim and desire to secure by Letters Patent is:

110 1. A double skip or kibble comprising a frame, two skips rotatably mounted there-

on, and means for moving said skips to a closed position in which the cutting edges of the skips are arranged out of contact with each other and in substantially vertical alignment.

2. A double skip or kibble comprising a frame, two skips rotatably mounted thereon, and means for moving said skips, one in advance of the other, to a closed position in which the cutting edge of one skip is above and out of contact with the other.

3. A double skip or kibble comprising a frame, two movable supports thereon, skips pivotally mounted on each of said supports, and means connected to said skips and supports for moving said skips, one in advance of the other, to their closed position in which the cutting edge of one skip is above and out of contact with the other.

4. A double skip or kibble comprising a frame, oscillatory supports thereon, skips pivotally mounted on said supports, a member movable with respect to said frame and links connecting said member to each of said

skips and supports respectively, said links being arranged to move one of said skips in advance of the other to their closed position in which the cutting edge of one skip is above and out of contact with the other.

5. A double skip or kibble comprising a frame, oscillatory supports thereon, skips pivotally mounted on said supports, a member movable with respect to said frame and links connecting said member to each of said skips and supports respectively, the links which connect the skips to said member being arranged to move one of said skips in advance of the other to their closed position, in which the cutting edge of one skip is above and out of contact with the other. 40

In testimony whereof, I have signed my name to this specification in the presence of two subscribing witnesses.

PAUL VOLKENBORN.
